(57) **CLAIM**

The ornamental design for a wearable sensor, as shown and described.

DESCRIPTION

FIG. 1 is a perspective view of a wearable sensor embodying our new design;

FIG. 2 is another perspective view thereof;

FIG. 3 is a top view thereof;

FIG. 4 is a left side view thereof;

FIG. 5 is a right side view thereof;

FIG. 6 is a front view thereof; and,

FIG. 7 is a back view thereof.

Broken lines, where shown, are used to illustrate portions of the wearable sensor that form no part of the claimed design. The dot-dash-dot lines form bounds of the claimed design and are not part of the claimed design.
